UNITED STATES PATENT OFFICE.

MAX BROWN, OF CHICAGO, ILLINOIS.

COLLAPSIBLE SLED.

1,384,553.

Specification of Letters Patent. Patented July 12, 1921.

Application filed November 10, 1919. Serial No. 337,092.

To all whom it may concern:

Be it known that I, MAX BROWN, a citizen of the United States, and a resident of the city of Chicago, county of Cook, and State 5 of Illinois, have invented certain new and useful Improvements in Collapsible Sleds, of which the following is a specification.

My invention relates to improvements in collapsible sleds, and has for its object the 10 provision of an improved construction of this character which is adapted to be folded into compact form, and which is durable and efficient in use, the present invention constituting an improvement over that disclosed 15 in my prior application, Serial No. 229,046, filed April 17, 1918.

Other objects will appear hereinafter.

The invention consists in the combinations and arrangements of parts hereinafter described and claimed.

The invention will be best understood by reference to the accompanying drawings forming a part of this specification, and in which,

25 Figure 1, is a top plan view of a collapsible sled embodying the invention,

Fig. 2, a side view of the same,

Fig. 3, a side view showing the sled collapsed and secured in collapsed form,

30 Fig. 4, a longitudinal section of the sled showing the parts in an intermediate position during the folding or collapsing operation,

Fig. 5, an enlarged detail view of a knee 35 joint arrangement employed in the construction,

Fig. 6, a section taken on line 6-6 of Fig. 5,

Fig. 7, a section taken on line 7-7 of 40 Fig. 5,

Fig. 8, a section taken on line 8-8 of Fig. 5,

Fig. 9, a detail view illustrating a latch 45 arrangement employed in the construction, and

Fig. 10, a side view corresponding with Fig. 9.

The preferred form of construction, as 50 illustrated in the drawings, comprises side angle bars 8 and angle runners 9 positioned thereunder and collapsibly connected thereto by means of foldable links 10 pivoted to the angle bars and the runners and to each other, forming knee joints, there being two sets of 55 said links connecting each side bar with its corresponding runner. Each of said links

10 is pivoted to the corresponding side bar and runner, and the members of each pair of links are pivoted together at the point 11, as shown. Each link is provided with a shoulder 12 adapted to contact with the corresponding side bar or runner to limit the outward swing or movement thereof, and with a lug or ear 13 adapted to contact with a similar lug or ear on the other link, also to 60 limit the outward swing thereof and stiffen and strengthen the construction. Each of the links 10 is also provided with a catch 10' adapted and arranged to automatically and 65 yieldingly interlock with the corresponding catch on the other corresponding link when said links are swung outwardly and thus yieldingly hold the sled in distended form. By this arrangement, it will be observed that each side bar 8 will be securely and rigidly 70 supported from the corresponding runner 9 when the links 10 are swung outwardly, as shown in Figs. 2 and 5, and that by raising the side bars 8 the links 10 may be readily 75 swung inwardly, as indicated in Figs. 4 and 80 3, thus breaking the knee joint and permitting of the collapsing or folding of the side bars onto the runners when desired.

The opposite sets of links 10 have their 85 pivotal joints 11 connected by links 14, which are pivotally connected, at their inner ends, and each pair of which is provided with a lug 15 adapted to engage a notch 16 to limit the swing of said links and form a knee joint between the opposite sets of links 90 10, and which, when the side bars 8 are collapsed onto the runners 9, assume horizontal and parallel positions and may then be readily broken or swung outwardly to permit of the approach of the opposite side bars and 95 runners, as indicated in Fig. 3. A spring held latch 15' is also provided on each pair of links 14 and arranged and adapted to automatically engage the corresponding lug 15 and lock the same in its corresponding 100 lug 16, thereby further stiffening and strengthening the construction. Each latch 15' is provided with a finger piece 16' by means of which the same may be released when it is desired to fold or collapse the 105 sled. In like manner, the side bars 8 are connected by a similar set of links 17, identical in all respects with the links 14, and likewise provided with latches 15', and whereby said side bars may be readily folded 110 together, as indicated in Fig. 3. By this arrangement, it will be observed that after

the side bars have been folded onto the runners, the opposite side bars and runners may be again folded onto each other, thus assembling the parts into very compact 5 form.

The top of the sled consists of two transverse bands or straps 20, of canvas or other suitable material, having one of their ends 10 permanently secured to one of the side bars 8 and the other ends equipped with metallic plates having key-hole slots 21 therein, adapted to engage studs 22 on the other side bar 8, as shown. Longitudinal slats 23 are secured to the bands 20, constituting the top 15 of the sled, and a strap 24, having a buckle 25, is arranged on each band 20 under the slats 23. By this arrangement, it will be observed that when the frame of the sled has been collapsed and folded, as above 20 described, the foldable top of the sled may be readily folded about said frame and secured in place by means of straps 24 and buckles 25. It will also be observed that a sled is thus provided which may be readily collapsed and 25 folded into compact form, or readily distended into usable form, and which is strong and efficient in use.

While I have illustrated and described the preferred form of construction for carrying 30 my invention into effect, this is capable of variation and modification without departing from the spirit of the invention. I therefore, do not wish to be limited to the precise details of construction set forth, but desire to 35 avail myself of such variations and modifications as come within the scope of the appended claims.

Having described my invention, what I 40 claim as new and desire to secure by Letters Patent is:—

1. A sled comprising a collapsible frame consisting of longitudinal bars; a plurality of knee joint connections between said bars, each consisting of two links pivoted to each 45 other and to said bars, one of said links being provided with a lug, there being a notch in the other link to receive said lug and inter-

lock therewith to prevent further bending of said knee joint; and a spring held catch arranged on said other link and adapted to engage said lug to hold the same in said notch, substantially as described. 50

2. A sled comprising a collapsible frame consisting of longitudinal bars; a plurality of knee joint connections between said bars, 55 each consisting of two links pivoted to each other and to said bars, one of said links being provided with a lug, there being a notch in the other link to receive said lug and interlock therewith to prevent further bending 60 of said knee joint; and a spring-held catch mounted on said other link and adapted and arranged to automatically interlock with said lug to hold said lug in said notch, substantially as described. 65

3. A sled comprising a collapsible frame consisting of longitudinal bars; a plurality of knee joint connections between said bars, each consisting of two links pivoted to each other and to said bars; and interlocking 70 catches on said links arranged to automatically engage with and disengage from each other and yieldingly hold said links in distended form, substantially as described.

4. A sled comprising a collapsible frame 75 consisting of longitudinal bars; a plurality of knee joint connections between said bars, each consisting of two links pivoted to each other and to said bars; interlocking catches on said links arranged to automatically engage with each other and yieldingly hold said links in distended form; and stop shoulders on said links arranged to engage and limit the movement of said links after automatic engagement between said catches, 80 substantially as described. 85

In testimony whereof I have signed my name to this specification in the presence of two subscribing witnesses.

MAX BROWN.
